UNITED STATES PATENT OFFICE.

JAMES H. BLESSING, OF ALBANY, ASSIGNOR TO THE NEW YORK FILTER COMPANY, OF NEW YORK, N. Y.

COAGULANT-FEEDER.

SPECIFICATION forming part of Letters Patent No. 510,112, dated December 5, 1893.

Application filed March 16, 1892. Serial No. 425,153. (No model.)

To all whom it may concern:

Be it known that I, JAMES H. BLESSING, of the city and county of Albany, in the State of New York, have invented new and useful 5 Improvements in Automatic Devices for Feeding Liquid Coagulants into Water-Purifying Apparatus, of which the following is a specification.

This invention relates to improvements on 10 the apparatus for which Letters Patent of the United States No. 412,910 were granted to me on the 15th day of October, 1889; and the object of my present invention is to provide facilities for rendering the apparatus capable 15 of a very delicate adjustment, so that an exceedingly minute quantity of the coagulant can be automatically introduced into a predetermined quantity of water to effect the purification of the latter. In the purification 20 of some waters a single drop of liquid coagulant to a gallon of the water is found to be ample to effect the precipitation of any organic matter that is held in suspension by the water, while in other waters the proportion 25 of the coagulant to a gallon of water requires to be largely increased to effect a like purpose. In an apparatus of this character, wherein a delicate adjustment of the parts is absolutely a necessity, it is very essential 30 that the parts which govern the admission of the coagulant should be kept as far as possible from the solution in its greatest strength, for the reason that the corrosive action would quickly destroy the parts and render the adjustment 35 a futility. It is also essential, when this apparatus is used for household purposes—which is a use for which it is largely intended—that the parts which regulate the quantity of the chemical to be admitted into 40 the water, should be placed beyond interference from an ordinary domestic servant.

In the accompanying drawings, which illustrate a mechanism for attaining the object above stated and which, being herein referred 45 to, forms part of this specification—Figure 1 is a side elevation of my invention applied to the water-supply pipe of a water-purifying apparatus. Fig. 2 is a plan view of the same. Fig. 3 is an enlarged vertical section of the 50 automatic-valve mechanism for controlling the flow of water into the water-purifying ap-

paratus and into the chamber for containing the coagulant, the parts being in position to stop the flow of water into either portion of the apparatus. Fig. 4 is a like section showing the parts in position to allow the water to flow into the water-purifying apparatus and coagulant-chamber. Fig. 5 is an enlarged vertical section of the coagulant-chamber. Fig. 6 is a horizontal section of Fig. 3 at the line X X. Fig. 7 is a horizontal section of Fig. 4 at the line Y Y. Figs. 8 and 9 are enlarged horizontal sections of Fig. 3 at the line Z Z, showing the valve for controlling the flow of water into the coagulant-chamber at 60 two different points of its adjustability. Figs. 10 and 11 are enlarged and detached side elevations of the valve for controlling the flow of water into the coagulant-chamber, showing said valve adjusted at different points of its 65 adjustability; and Fig. 12 is a plan view of the valve-casing with its bonnet removed and the valve-stem in horizontal section.

As represented in the drawings, A designates a water-purifying apparatus of a well-known form, which I preferably use for this purpose, but it should be understood that my present invention can be profitably used in conjunction with any water-purifying apparatus that operates under pressure.

B designates the valve-casing for containing the valve mechanism of my device.

C designates the coagulant-chamber which is usually made in cylindrical form and preferably of glass, so that the condition of its 85 contents can be readily examined. Preferably the coagulant used in said chamber is in the form of crystals.

The valve-chamber B has a cylindrical bore in which a cylindrical bushing, D, is tightly 90 fitted to reduce the upper portion of said bore. An annular passage, E, is formed near the upper end of said casing; said passage being formed by an enlargement of the bore of the casing and the outer surface of the 95 bushing D; the latter is provided with a series of perforations, 1, leading from the passage E into the bore of said bushing. Said perforations are arranged at different planes in a vertical direction and at each plane a 100 series of the perforations are made to extend from the bore of said bushing to the passage

E, as shown in Fig. 7, and the combined openings of said perforations should have an excess of area over that of the passage F through which the water is conveyed into the apparatus, under pressure, by means of a supply pipe, G, which leads from the mains of a water-system. The valve-casing B contains a small filtering-chamber, H, which lies directly below the passage F, and from the latter a passage, 2, leads directly into said filtering-chamber for the purpose of conveying a portion of the inflowing water thereinto. The filtering-chamber H contains a filling of sponge or other porous material that will remove the grit, and other substances that will be injurious to the lowermost valve of the device, while the water is percolating through the filtering material in said chamber; the filtering material is introduced into the chamber H by means of an opening, 3, which is closed by a screw-plug, 4, which forms a water-tight closure for said opening. At the lower part of the chamber H an opening, 5, leads into the lower portion of the bore of the valve-casing B for the purpose of conveying the filtered water from the chamber H into the lower portion of said valve-casing. I designates a valve-stem which is provided with an upper-valve, J, and a lower-valve, K, both of which are made in the form of pistons, and are fitted to slide easily in the bore of the bushing D. The upper-valve J is provided with one or more openings, 6, for a purpose hereinafter explained. A loose valve, L, is fitted to slide loosely on the upper portion of the valve-stem I, and said valve is designed to close the upper end of the bore of the bushing D. The valve L has its hub, 7, bored to leave a leakage around the valve-stem I, for the purpose of allowing water to pass into the bore of the bushing—under conditions hereinafter set forth—from the chambered-bonnet, M, which covers the upper end of the valve-casing B. From one side of the valve-casing B an outlet-pipe, N, projects to convey the water from said valve-casing; preferably said outlet-pipe is arranged at the opposite side of the valve-casing from the supply-pipe G, and the distance between the valves J and K should be sufficient to avoid any danger of either of said valves closing over the opening of the outlet-pipe N. In order to avoid any liability of the stoppage of the leaky joint of the hub 7 with the valve-stem I, a small opening, 8, is formed in the valve L, as shown in Figs. 3 and 12. The valves J and K are fitted to reciprocate in the bore of the bushing D, and normally the valve J will remain at the lowest point of its movement to close all of the perforations 1—as shown in Fig. 3—and thereby the flow of water through the valve-casing B will be prevented. For the purpose of reducing the pressure of the outflowing water below that of the inflowing current, a weight, 9, is attached to the

valve-stem I, and said weight should be proportioned to effect the required reduction in said pressures. The weight 9 is preferably arranged to be in the chamber formed by the bonnet M wherein it will be removed from interference on the part of those who are unauthorized to adjust the apparatus. It should be understood that the weight 9 should be proportioned to the area of the bore of the bushing D to effect the required reduction of pressure under all variations of the latter. For instance if the area of the bore of the bushing D is five square inches, and it is required to reduce the pressure of the outflowing water one pound per square inch below that of the incoming water, the weight 9 will require to be just five pounds to produce a reduction of one pound to the square inch regardless of the variations of pressure of the incoming water.

To the lower end of the valve-casing B there is attached a cylindrical extension, O, whose bore is of a less diameter than that of the bushing D, but preferably said bores should be exactly centralized and in true alignment with each other. A tubular piston-valve, P, is fitted to reciprocate in the bore of said extension. Said valve is connected to the lower end of the valve-stem I by means of a coupling, 10, which will allow a slight degree of flexion to suit any variation in the alignment of the bores of the bushing D and extension O. Preferably said coupling is made in the form shown in Letters Patent of the United States No. 310,870, granted to me January 20, 1885, for improvements in revoluble joints for valve-stems.

The valve P is composed of an inner cylinder, 11, and an outer cylinder, 12, which is fitted to reciprocate in the bore of the extension O, and is bored to fit snugly on the periphery of said inner cylinder, to which it is secured by means of a nut, 13, fitted to screw onto the lower end of said inner cylinder; the latter has a longitudinal opening, 14, which extends upwardly from its lower end which remains constantly open. Said inner cylinder is provided with a collar, 15, which forms a seat for the upper end of the outer cylinder which is provided with a circumferential flange, 16, whose diameter is preferably made to correspond to that of said collar.

The inner and outer cylinders, 11 and 12, are both provided with a series of openings, 17, which correspond in both of said cylinders and are spaced in correspondence to the perforations 1 of the bushing D; said openings lead into the longitudinal opening of the inner cylinder 11, and by a rotative adjustment of the inner and outer cylinders the effective area of said openings can be regulated to suit the different conditions under which this apparatus may be required to operate.

For the purpose of indicating the adjustment of the openings 17 in the outer cylinder with those of the inner cylinder, an index, or graduated scale, 18, is made on the periphery

of the valve P, and said openings can be readily adjusted in the following manner: The bonnet M is first removed from the valve-casing B, and the valve-stem I, with its attached 5 valves, is drawn out of the bore of said valve-casing, whereby free access is obtained to the valve P; the nut 13 is then slackened to free the outer cylinder 12 so as to allow either of the cylinders, 11 or 12, to be turned to bring 10 the openings 17 into the required adjustment, after which the nut 13 is tightened to hold the two cylinders; after which the valve-stem I, and its attachments, is restored to its place, and the bonnet M is secured, thereby leaving 15 the apparatus in condition for operation.

Leading from the lower end of the extension O there is a pipe, Q, which connects with the upper end of the coagulant-chamber C, said pipe being carried downward in said 20 chamber nearly to the bottom of the latter, so that the water flowing through said pipe will be delivered into the lower end of the coagulant-chamber and be carried into contact with the coagulant contained therein, thereby effecting 25 a thorough saturation of the water before it rises to the upper end of said chamber. An opening in the top of said chamber—provided with a stopper 19—affords the means for charging the chamber C with the coagulant, and a similar opening in the bottom of 30 said chamber—provided with a stopper 20—affords the means for discharging any sedimentary deposit therefrom.

The coagulant-chamber is provided with a 35 top-plate, 21, and a bottom-plate, 22, both having an annular groove, 23, for receiving the corresponding end of the cylinder 24, and each groove having an elastic annulus, 25, which forms a water-tight joint for said cylinder. The top and bottom plates are each provided with lugs, 28, projecting from opposite edges of same. Said lugs are slotted—so as to be open at one side—to receive the binding-bolts, 27, which draw said plates closely against 40 the ends of the cylinder 24 to form a water-tight joint therewith. From the top-plate 21 a coagulant-pipe, 28, leads upwardly and is connected to the outlet-pipe N, said coagulant-pipe being provided with a check-valve, 45 29, to prevent the water that passes through the outlet-pipe N from getting back into the coagulant-pipe. Preferably the pipes Q and 28 are each provided with a stop-valve for the purpose of closing the passages through said 50 pipes; said stop-valves being respectively designated as 30 and 31. The outlet-pipe N connects with a branch-pipe, R, to convey water, either in the condition in which it is received from the mains or with coagulant 55 mixed therewith, into the water-purifying apparatus.

When my invention is applied to a water system wherein a hot-water boiler is included provision is required for relieving the apparatus from the extra pressure produced by the 60 expansion of the water by heat. Said provision is made by means of the openings 6—in

the valve J—valve L, openings, 32, which lead from the belt-passage E into the chamber of the bonnet M, so that, when the valve J is in 70 the position shown in Fig. 3 to effect the closing of the perforations 1, on the occurrence of a backward pressure, the water will be forced upwardly through the openings 6, and, after forcing the valve L to lift, downwardly, by the 75 openings 32, into the passage E, and thence into the passage F to force backward the water toward the mains whereby it is supplied.

My invention operates in the following manner: The coagulant-chamber C being charged, 80 in the manner hereinbefore described, with coagulant crystals which are readily soluble in water, the valves 30 and 31 are opened for the purpose of allowing the water to flow downward through the pipe Q and the liquid 85 coagulant to flow upward through the pipe 28 into the pipe N to commingle with the current of water which flows through the pipe N, the proportion of the coagulant solution to a predetermined quantity of water being 90 regulated by adjusting the cylinders 11 and 12 to either increase or diminish the area of the openings 17 as occasion may require. So long as no water is being drawn from the purifying apparatus A the pressures on the lower 95 face of the valve J and the upper face of the head K will be virtually balanced, so that the weight of the valve-stem I and its attachments will depress the valve J, and thereby effect the closing of the perforations 1, but as 100 soon as the water-purifying apparatus A is opened, to allow the water to flow therefrom, the pressure acting upon the upper face of the head K will be reduced to a degree that will allow the pressure acting upon the lower 105 face of said head to force the valve-stem I, and its parts, to move upwardly and carry the valve J from covering the perforations 1; coincidently with the upward movement of the valve J, the valve P will be moved upwardly 110 to successively carry the openings 17 above the upper end of the extension O to uncover said openings; the uncovering of each row of the perforations 1 will occur simultaneously 115 with the uncovering of the corresponding openings 17 in the valve P, thereby allowing a predetermined quantity of the partially filtered water from the chamber H to percolate through the openings 17 and thence downwardly, through the pipe Q, into the lower 120 part of the coagulant-chamber C, to displace the same quantity of the coagulant-solution from said chamber. The quantity of solution so displaced will flow upwardly, through the pipe 28, and be discharged into the pipe 125 N, wherein said solution will commingle with the current of inflowing water to effect a precipitation of the matter held in suspension in said water. Said precipitation is readily separated from said water, when treated as above 130 described, by passing the water through the filtering-material contained in the water-purifying apparatus A. The valve J, during the first of its downward movements, and un-

til it has effected the closing of the perforations 1, descends rapidly. Then it settles down gradually until the flange 16 bears closely upon the upper face of the extension 5 O, to form a water-tight joint at that point. The final descending movement of the valve J will equal the distance that the lower part of said valve overlaps the lower perforation 1, and said descending movement is facilitated 10 by the water which flows upwardly through the openings 32 and thence downwardly, through the leakage between the bore of the hub 7 and valve-stem I, and through the openings 6, into the space between the 15 valve J and head K to re-establish an equilibrium of pressure in said space. In my earlier device, as covered by my former patent hereinbefore referred to, the liquid coagulant was carried into the valve-casing and wherein it is liable to effect a corrosion of the parts that will interfere with its operation. In this present device the liquid coagulant does not enter the valve-casing nor any part 20 wherein a corrosive action of said coagulant will affect the operativeness of the apparatus, and, by reason of the provision made for the delicate adjustment of the openings through the valve P, the proportion of liquid coagulant to a given quantity of water can be reduced 25 to such an infinitesimal quantity that any noxious quality that said coagulant might possibly possess will be rendered perfectly harmless, while the potency of the solution for effecting the precipitation of matter held in suspension by the water will remain. 30

What I claim as my invention, and desire to secure by Letters Patent, is—

1. An attachment for automatically controlling the supply of liquid coagulant fed into a water-purifying apparatus, the same consisting of a valve-casing containing an automatic valve which controls the flow of water into the water-purifying apparatus and 40 an auxiliary valve attached to said automatic valve for the purpose of governing the flow of water into a coagulant-chamber, in combination with a coagulant-chamber, a coagulant-pipe leading upwardly from said coagulant-chamber into a pipe leading from said valve-casing into the water-purifying apparatus; whereby the liquid coagulant will be fed into said water-purifying apparatus without entering said valve-casing, as and for the 45 purpose herein specified.

2. The combination of a valve-casing having a series of inlet-openings arranged to enter the bore of said casing at different planes, an

annular passage having direct communication with said openings, a water-supply passage leading into said annular passage and having a constantly-open branch leading into the lower part of the bore of said casing, a water-discharge passage leading laterally from said bore, an automatic water-controlling valve consisting of two connected pistons or heads which are fitted to slide in the bore of said valve-casing and to form a communicating passage between said water-discharge passage and inlet-openings; the lower piston forming a closure for said bore between said water-discharge passage and the branch of the water-supply passage, and an auxiliary valve operated by said automatic water-controlling valve and fitted to slide in an extension of said casing; said auxiliary valve being provided with a series of outlet openings for controlling the flow of water into a coagulant-chamber, as and for the purpose herein specified. 60 65 70 75 80

3. The combination with a valve-casing having a water-supply passage leading into an annular passage provided with a series of inlet openings arranged to communicate with the bore of said casing at different planes, a 85 filtering chamber which forms a communication between said water-supply passage and the lower part of the bore of said casing, an automatic valve which controls the flow of water into a water-purifying apparatus; said valve consisting of two connected pistons or heads fitted to slide in the bore of said casing and forming a communicating passage between said inlet openings and a water-discharge passage which leads laterally from the 90 bore of said casing, and a tubular auxiliary valve operated by said automatic valve, whereby the supply of water flowing into an attached coagulant-chamber will be controlled, as and for the purpose herein specified. 95 100

4. The combination of a water-purifying apparatus, an automatic-valve for controlling the flow of water into said apparatus, an auxiliary valve connected to and operated by said automatic-valve and arranged to control 105 the flow of water into a coagulant-chamber, and a coagulant-chamber provided with a coagulant-pipe arranged to discharge liquid coagulant into the water-supply pipe of the water-purifying apparatus, substantially as 110 and for the purpose herein specified.

JAMES H. BLESSING.
